United States Patent Office

Des. 193,925
Patented Oct. 23, 1962

193,925

TEXTILE FABRIC

Oscar Hyman, Bayside, N.Y., assignor to Colony Textiles, Inc., New York, N.Y., a corporation of New York

Filed Mar. 26, 1962, Ser. No. 69,407

Term of patent 3½ years

(Cl. D92—1)

The FIGURE is a top plan view of a textile fabric, showing my new design.

The design is continuous in the horizontal direction.

I claim:

The ornamental design for a textile fabric, as shown and described.
